SYSTEM FOR HANDLING ARTICLES

Howard W. Wylie, Seattle, Wash., assignor, by
mesne assignments, to Standard-Knapp Cor-
poration, Portland, Conn., a corporation of New
York

Application May 4, 1942, Serial No. 441,735

9 Claims. (Cl. 214—1.1)

My invention relates to the handling of articles, such as cans; and more particularly to means for inverting a tray of cans to facilitate removal of the tray.

In canneries where cans are handled in batches, the cans come from the cooker in trays. The problem is then to remove the cans from the tray without denting or otherwise damaging the cans preparatory to feeding the cans to the labeler. It is among the objects of my invention to provide a mechanism for inverting a tray full of cans so that the tray may be removed by simply lifting it off the batch of cans.

Another object is to provide an inverting device of the character described which operates in conjunction with means for moving the inverted cans from the device, whereby the tray may be lifted from the cans as the latter travel along a path toward a discharge mechanism.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawings:

Figure 1 is a side elevational view showing the left-hand portions of apparatus embodying the improvements of my invention; and

Figure 2 is a similar view showing the right-hand portion of the apparatus.

Figure 3 is a fragmentary plan view showing the can receiving platform; and

Figure 4 is a similar view of the discharge mechanism.

In terms of broad inclusion, my improved system for handling articles embodies an inverting device comprising a pair of hingeably connected platforms, and means for mounting the platforms for movement between open and closed-book positions for transferring articles on one of the platforms to an inverted position on the other platform. Means are preferably provided for moving the articles along a path from the inverting device toward a discharge mechanism; and means are further preferably provided for converging the articles as they travel along the path.

In greater detail, and referring to the drawings, my apparatus for handling a batch of cans

2 in a tray 3 includes an inverting device comprising a pair of hingeably connected platforms 4 and 6 mounted at the head end of a main frame 7. In their normal position these platforms are extended like an open book as shown in solid lines in Figure 1; the extended platforms lying in a common horizontal plane in line with the bed of the apparatus. Platform 4 receives the tray of cans, and has a plurality of freely journaled bed rollers 8 upon which the tray rests so that the

tray will ride easily into position on the platform. It is convenient to provide a table (not shown) also having surface rollers, adjacent the head end of my apparatus so that the tray may be shoved from the table onto platform 4. Any suitable means however may be provided for depositing the tray on the platform.

The hinge connection between the platforms comprises a pin or rod 9 carried by uprights 11 on platform 6, which rod extends through a circular bar 12 on uprights 13 of platform 4. This places the hinge axis above the plane of extended platforms, and positions bar 12 so as to provide a rounded abutment for the end of the tray.

Means are provided for mounting the platforms for movement from the extended or open-book position to the parallel or closed-book position illustrated by dotted lines in Figure 1. In the closed position the platforms are substantially vertical with the tray of cans sandwiched therebetween. The rounded hinge bar 12 upon which the vertical tray rests is disposed back of the center of gravity of the load just enough to cause the cans and tray to tip over against platform 6, so that when the device is folded back to normal position the cans and tray will ride down in inverted position on platform 6.

Platform 6 is preferably mounted on a fixed pivot comprising a pin or rod 14 carried by the framework of the platform and journaled in bearings 16 on side members of the main frame 7. The other platform 4 is mounted on a moving pivot comprising an axle 17 on the platform framework and having wheels 18 riding on a track formed by the side members of the main frame 7. The axes of the fixed and moving pivots are preferably disposed somewhat closer to the hinged ends than the outer ends of the platforms, so the platforms lie stable in the extended positions rather than tending to buckle together. The balance is such, however, that an operator may readily fold the platforms together by lifting up on a suitable handle 19, preferably provided on platform 4.

Platform 6 has a plurality of freely journaled bed rollers 21. These are preferably elongated tubes extending transversely of the platform, journaled on cross-rods 22 supported by the platform framework, and forming a bed upon which the inverted cans rest.

Means are further preferably provided for moving the inverted cans and overlying tray from platform 6 and advancing the batch of cans along a path toward the discharge end of the system. As shown in Figures 1 and 2, the bed of main frame 7 is also made up of freely journaled rollers 23 similar to those on platform 6. These bed rollers are driven by a belt 24 having an upper reach frictionally engaging the under sides of the rollers. A series of subframes 26 are spaced

along the main frame and carry rollers 27 for pressing the belt against the bed rollers. These subframes are adjustably mounted, as by adjusting screws 28, for maintaining proper belt pressure against the bed rollers. The belt passes around a pulley 29 adjacent the discharge end of the apparatus, and about a pulley 31 disposed under platform 6 to the right of its pivot axis. By this arrangement a portion of the drive belt underlies some of bed rollers 21 of the platform, so that when the latter is in extended position these rollers are also positively driven. The batch of inverted cans is thus started in their forward movement through the system as soon as the platform is brought down into its extended position. It is unnecessary that all of bed rollers 21 on the platform be positively driven, because the tray still embraces the batch at this time and all is driven forwardly as a unit.

End pulleys 29 and 31 for the drive belt are preferably journaled in brackets 32 suitably mounted for vertical adjustment on the main frame. From these pulleys the lower reach of belt 24 extends along the under side of the main frame, over suitable guide pulleys 33; about an adjustable idler 34 for maintaining tension; and over a drive pulley 35 on shaft 36. The latter is driven by a motor 37 through a suitable drive connection 38. The motor and associated pulleys are preferably mounted in an enclosed frame 39 suspended from the under side of the main frame.

As the batch of inverted cans is advanced along the bed of the apparatus, the overlying tray is removed, preferably by operators standing on opposite sides of the machine. At this time all of the cans are resting on the driven bed rollers, so that upon removal of the tray the cans continue to advance as a group.

In my preferred system the cans are discharged singly by means of a centrifugal feeder comprising a disk 41 disposed in the plane of the machine bed at the discharge end of the apparatus. The cans are converged toward the disk by guide plates 42 extending angularly across bed rollers 23 and terminating at the mouth of a circular guide plate 43 which lies about the periphery of disk 41. Plates 42 are suspended from suitable cross members 44 on the main frame, and are hinged to arcuate sections 46 adjustably mounted on circular plate 43 to control the size of the opening.

Disk 41 is rotated clockwise as viewed in Figure 4 by a vertical shaft 47 depending from the disk and journaled in suitable bearings 48 on the main frame. The lower end of this shaft carries a bevel gear 49 meshed with another gear 51 on a cross shaft 52 journaled in bearings 53 as indicated in Figure 4. Shaft 52 is in turn driven from pulley shaft 36 by a suitable drive connection 54.

As the cans converge onto disk 41 they are moved outwardly against circular plate 43 by the action of centrifugal force, and are advanced in single file toward discharge chute 56. This chute is preferably twisted through 90° as illustrated in Figures 2 and 4, so that the cans roll out on their sides in position to be carried along by any suitable conveyor to the labeler.

I claim:

1. An inverting device comprising a pair of hingeably connected platforms, a fixed pivot for one of the platforms, a movable pivot for the

other platform, and a track along which the movable pivot may ride.

2. An inverting device comprising a frame, a pair of hingeably connected platforms, means on the frame for pivotally mounting one of the platforms about a fixed axis, and means on the frame for pivotally mounting the other platform about a movable axis.

3. An inverting device comprising a frame, a pair of hingeably connected platforms, means on the frame for pivotally mounting one of the platforms about a fixed axis, and means including a wheel riding on the frame for pivotally mounting the other platform.

4. In an apparatus for reversing the position of articles, a frame, a platform for delivering the articles and pivotally mounted on the frame and for movement therealong, and a platform for receiving the articles and pivotally mounted on the frame for movement about a fixed axis and also pivoted to the delivering platform, the points of pivoting of the platforms on the frame being closer to the pivotal connection between the platforms than to the opposite ends of the platforms so that the platforms tend to remain in aligned relation on the frame.

5. In an apparatus for reversing the position of an article, a pair of pivotally connected platforms one for delivering and one for receiving the article to be reversed, and means for mounting the platforms for movement between aligned and parallel positions, and a pivoting support for the side of the article and disposed at the delivering platform side of the center of gravity of the article to cause tipping of the article toward the receiving platform when the platforms are in vertical position.

6. An inverting device comprising a pair of hingeably connected platforms, a fixed pivot for one of the platforms, a movable pivot for the other platform, and a track along which the movable pivot may ride, said pivots being disposed to support their respective platforms in a condition of approximately balanced equilibrium.

7. An inverting device comprising a frame, a pair of hingeably connected platforms, means on the frame for pivotally mounting one of the platforms about a fixed axis in approximately balanced equilibrium, and means on the frame for pivotally mounting the other platform in approximately balanced equilibrium about a movable axis.

8. An inverting device comprising a frame, a pair of hingeably connected platforms, means on the frame for pivotally mounting one of the platforms about a fixed axis in approximately balanced equilibrium, and means including a pair of wheels riding on the frame for pivotally mounting the other platform in approximately balanced equilibrium.

9. In an apparatus for reversing the position of articles, a frame, a platform for delivering the articles and pivotally mounted on the frame and for horizontal movement therealong, and a platform for receiving the articles and pivotally mounted on the frame for movement about a fixed axis and also pivoted to the delivering platform, the points of pivoting of the platforms on the frame being disposed to produce an approximately balanced equilibrium of the platforms but being closer to the pivotal connection between the platforms than to the opposite ends of the platforms so that the platforms tend to remain in aligned relation on the frame.

HOWARD W. WYLIE.
